UNITED STATES PATENT OFFICE

157,337

MEDICAMENT RECEPTACLE

Vernon E. Britt, San Jose, Calif.

Application April 18, 1949, Serial No. 2,110

Term of patent 3½ years

(Cl. 86—10)

To all whom it may concern:

Be it known that I, Vernon E. Britt, a citizen of the United States and a resident of San Jose, county of Santa Clara, State of California, have invented a new, original, and ornamental Design for a Medicament Receptacle, of which the following is a specification, reference being had to the accompanying drawing, forming part thereof.

I claim:

The ornamental design for a medicament receptacle, substantially as shown.

VERNON E. BRITT.
